UNITED STATES PATENT OFFICE.

PAUL VOREAUX AND RAYMOND BABEL, OF PARIS, FRANCE.

ROTARY APPARATUS OPERATING AS PUMP OR MOTOR.

Application filed August 10, 1920. Serial No. 402,726.

To all whom it may concern:

Be it known that we, PAUL VOREAUX and RAYMOND BABEL, citizens of the Republic of France, residing at Paris, France, have invented certain new and useful Improvements in Rotary Apparatus Operating as Pump or Motor, of which the following is a specification.

This invention relates to a rotary apparatus which is designed to operate as a pump or a motor, and makes use of fluids of all kinds, either liquids or gases.

The apparatus comprises on the one hand a star-shaped cylinder combination rotating about a stationary shaft serving as the valve gear for inlet and delivery of fluid, and on the other hand a main casing which draws along the pistons in its rotational motion about an axis having an eccentric disposition with reference to the axis of the star-shaped cylinder combination, in such manner as to cause variations in the volume comprised between the head of each piston and the stationary shaft having the cylinders rotating thereon, and thus to effect the circulation of the fluid in case the apparatus works as a pump, or inversely, to effect the rotation of the apparatus if the compressed fluid is delivered into the cylinders.

One of the particular features of the invention resides in the method of assembling the different members of the apparatus, and chiefly in the method of connecting the pistons with the outer casing by means of rods secured to the latter, the said pistons being adapted to slide along these rods. Another special feature lies in the valve gear combination afforded by the rotation of the star-shaped cylinder makeup, this latter being employed for covering and uncovering the ports of the fluid intake and delivery passages, the said passages being provided in the stationary shaft having rotating thereon the star-shaped cylinder combination.

This invention also comprises various improvements designed to obviate the leakage which is liable to occur either between the cylinders, along the shaft, or in the main casing.

The following description and accompanying drawing given by way of example, explain how the invention can be carried out.

Fig. 1 is a cross-section of the apparatus perpendicular to its axis of rotation, this

section being taken along the line X—X of Fig. 2 with certain parts such as the pistons shown in exterior view.

Fig. 2 is a longitudinal section of the rotary apparatus partly in exterior view.

Figs. 3, 4 and 5 relate to an alternative form of the valve gear. Figs. 3 and 4 correspond to sections along Y—Y and Z—Z of Fig. 2 in which the valve gear is modified according to the said alternative form; Fig. 5 is a section through the end of the delivery passage.

Figs. 6 and 7 show respectively in vertical and in longitudinal section along the line 7—7 of Fig. 6, an apparatus containing the improvements designed to secure a better tightness.

The apparatus according to this invention comprises a star-shaped cylinder combination a^1, a^2, a^3 rotating about a stationary shaft b . The cylinders a^1, a^2, a^3 contain the pistons c^1, c^2, c^3 , traversed by the rods d^1, d^2, d^3 rigidly secured to the outer casing e which rotates upon the journals f mounted in fixed position but eccentric with reference to the shaft b .

It will be observed according to the foregoing that the cylinder combination a^1, a^2, a^3 rotates about the axis U—U of the stationary shaft, while the pistons c^1, c^2, c^3 rotate about the stationary shaft V—V of the journals f . Under these conditions, when the casing e rotates, carrying with it in its movement the cylinders a^1, a^2, a^3 and the pistons c^1, c^2, c^3 , these latter will also have a displacement relative to the cylinders a^1, a^2, a^3 , i. e., they will move within the cylinders with an amplitude of longitudinal displacement equal to one-half the value of the eccentricity between the axes U—U and V—V. This longitudinal movement of the pistons in the cylinders can take place by reason of the sliding disposition of the pistons along the rods d^1, d^2, d^3 .

Moreover, the journals f and the shaft b contain the passages h i for the intake and delivery of the fluid, admitting that the apparatus operates as a pump, i. e., that the casing e is given a rotary movement, for instance in the direction of the arrow, Fig. 1.

It will be observed that when the casing has made one-third of a revolution, the cylinder a^2 , which is drawn in the rotary movement of the casing e by the piston c^2 (which latter is drawn by the rod d^2 rigidly secured to the casing) has now taken the

place of the cylinder a^3 , and the piston c^2 has now arrived at c^3 . During its longitudinal displacement in the cylinder, the piston has set up a suction of the fluid, which latter arrives through h and enters the chamber j through the port k ; as the casing continues to rotate, the volume of the chamber j increases up to the point where the cylinder a^2 has rotated by 180 degrees, and then diminishes at once. As soon as the cylinder is connected to the port l having ending therein the exhaust passage i , the delivery of the fluid will take place in the said passage by reason of the fact that the volume of the chamber j diminishes.

When the casing has made a complete revolution, the cylinder a^2 and the piston c^2 have now come into the initial position for which the volume of the chamber j is zero or a very small value.

The foregoing conditions for a cylinder a^2 are equally applicable to all the other cylinders a^1 a^3 .

It will also be understood that the apparatus can be caused to rotate in the contrary sense to the arrow Fig. 1, and the fluid will now be drawn in through the passage i and delivered through the passage h . Instead of working as a pump or compressor as has just been described, the apparatus can also operate as a motor, in case fluid under pressure is sent through the passage h (in which event the apparatus will rotate according to the arrow Fig. 1) or through the passage i (in which case the apparatus will rotate in the contrary sense to the arrow).

The casing e may be closed by a cover m secured to the bosses of the casing for instance by means of the screws o .

Figs. 3, 4 and 5 relate to an alternative form of the special valve gear whereby the rotary apparatus can be employed either as a compressor or as a compressed fluid motor while preserving the same sense of rotation. The apparatus rotates in the sense of the arrows, and the end of the delivery passage i terminating in the journal f is closed by a check valve p , as shown in Fig. 5. The inlet passage can communicate with the chambers j of the cylinders through a passage h and a second passage h^1 provided with a check valve t , in the shape of a ball or valve maintained by a spring u whereby the cylinder begins to uncover the passage h^1 when at the lower end of the piston stroke and finishes uncovering the passage h when at the upper end of the piston stroke. For the delivery or offtake passage, the same method is employed, using the passages i and i^1 this latter being provided with the check valve y maintained by a spring c .

In case the delivery passage communicates with the compressed fluid tank and the inlet passage communicates with the fluid

to be compressed, for instance the outer air, the inlet takes place through the passage h , since the suction in the chamber j of the cylinder is not sufficient to overcome the resistance of the spring u of the check valve 70 t , while the delivery will take place through i , since the suction in the chamber j is not of sufficient value before the opening of the passage i to overcome the pressure of the spring x of the check valve v . Since the 75 valve p will open only when the pressure in the chamber j is superior to that of the tank containing the fluid or compressed gas, and on the other hand two cylinders cannot communicate with this tank, and again, the 80 inlet action only commences when a suction already exists in the cylinder, it will follow that the apparatus will work under good conditions of efficiency as a compressor.

If the delivery passage is connected with the outer air or the fluid to be compressed, and the intake is connected with the tank containing the fluid or compressed gas, the pressure of the latter will open the valve t , and the inlet will commence at the bottom 90 of the piston stroke and will continue throughout the whole of the stroke by way of the passages h^1 and h . This disposition affords the maximum power, and the apparatus can be started from all positions, 95 since one cylinder is always connected with the inlet passage. In like manner, during the delivery the pressure in the cylinder causes the valve v to open, and the delivery takes place during the entire stroke of the 100 piston by way of the passages i^1 and i .

In the foregoing apparatus the heads of the cylinders are formed by the stationary shaft b itself. This arrangement has various drawbacks, and chiefly tends to give rise 105 to leakage from one cylinder to another and to render the machine construction work on the piston very difficult.

To overcome this drawback, the applicants have substituted for the star-shaped 110 member a^1 a^2 a^3 , a member of the same description A^1 A^2 A^3 A^4 , having a star shape (Figs. 6 and 7) but containing as many cylinder heads J^1 J^2 J^3 J^4 as there are pistons C^1 C^2 C^3 C^4 , each cylinder head containing 115 a port R^1 R^2 R^3 R^4 connecting the corresponding cylinder head alternately with the fluid intake and delivery passages h i disposed in the shaft b .

Moreover, as will be seen in Fig. 7, the 120 longitudinal bearing surface of the member A^1 A^2 A^3 A^4 has been increased by the use of the circular extensions E F , employing also upon the shaft b the circular grooves F^1 filled with a plastic substance, fibre for instance, thus preventing leakage along the shaft b .

Another improvement which comes under the application, consists in the method of mounting the cross-shafts of the sliding pis- 125

tons, and these shafts D^1 D^2 D^3 D^4 are held at their ends in the bosses P^1 P^2 P^3 P^4 cast together with the main casing m , a soft metal ring, for instance in bronze Q^1 Q^2 Q^3 Q^4 being preferably disposed between each piston and its shaft. This disposition affords an absolutely tight construction for the casing, this casing being no longer provided with holes as in the preceding description.

It is of course understood that the sliding disposition of the pistons which is obtained simply by the use of a shaft having the piston sliding thereon, could be obtained in any other suitable manner, and chiefly by providing each piston with rollers, with a small carriage or with any other suitable sliding means.

This invention is not of course limited to the hereinbefore described arrangements, but is susceptible of various modifications and changes which would be within the spirit of the invention, and as a particular case it may be observed that the cylinders may be provided in any number.

Having thus described the nature of our said invention and the best means we know

of carrying the same into practical effect, we claim:

A rotary apparatus operating either as 30 compressor or motor, comprising a fan-shaped cylinder combination, a stationary hollow shaft having the said cylinder combination rotatable thereon, intake and delivery passages provided in the stationary 35 shaft, a main casing rotatable about an axis having an eccentric disposition with reference to the axis of rotation of the said cylinder combination, rods rigidly secured to the said casing and having the said pistons 40 slidably thereon, a valve disposed at the end of the delivery passage of the said stationary hollow shaft, an auxiliary intake passage disposed within the hollow shaft and provided with valves, and an auxiliary delivery passage disposed within the hollow 45 shaft and provided with valves.

In witness whereof, we have hereunto signed our names in the presence of the subscribing witness.

PAUL VOREAUX.
RAYMOND BABEL.

Witness:

CLEMENT S. EDWARDS.
